George G. Graessle.

UNITED STATES PATENT OFFICE.

GEORGE G. GRAESSLE, OF SEYMOUR, INDIANA.

DESIGN FOR A CALENDAR AND PAPER-WEIGHT.

SPECIFICATION forming part of Design No. 27,519, dated August 17, 1897.

Application filed February 4, 1897. Serial No. 622,045. Term of patent 7 years.

To all whom it may concern:

Be it known that I, GEORGE G. GRAESSLE, a citizen of the United States, residing at Seymour, in the county of Jackson and State of Indiana, have invented a new and original Design for a Combined Calendar and Paper-Weight, of which the following is a specification.

This invention relates to a new and original design for a combined calendar and paper-weight; and it has for its object to provide a design of this character that shall be both useful and ornamental.

The leading feature of the design resides in a rectangular body formed in its front face at a point between its longitudinal side edges with a pair of adjacent parallel longitudinal openings of a narrow rectangular form and extending nearly the entire length of the body, and a pair of spaced longitudinally aligned short rectangular openings disposed adjacent to one edge of the body, the common longitudinal plane of the short openings being parallel with the plane of the longer openings, said body being further provided in its side and end edges with elongated angular depressions.

Figure 1 is a perspective of a combined calendar and paper-weight embodying the

herein-described design, showing the obverse 30 side thereof. Fig. 2 is a plan view of the reverse side of the same.

Referring to the drawings, the numeral 1 designates the rectangular body of the combined calendar and paper-weight formed in 35 its front face, between the longitudinal side edges thereof, with a pair of adjacent parallel longitudinal openings 2, of a narrow rectangular form, and extending nearly the entire length of the body. The body is also formed 40 in its front face with short rectangular openings 3, which are longitudinally aligned adjacent to one side edge of the body and are also disposed parallel with the planes of the longer openings 2.

The design is completed by forming elongated angular depressions 4 in the side and end edges of the body.

What I claim is—

The design for a combined calendar and 50 paper-weight herein shown and described.

In testimony that I claim the foregoing as my own I have hereto affixed my signature in the presence of two witnesses.

GEORGE G. GRAESSLE.
